ABSTRACT

Reducing gas containing CO and H₂ as the major ingredients is prepared by partially oxidizing a hydrocarbon oil with oxygen or oxygen rich air to produce an intermediate gas containing CO₂ and H₂O and converting CO₂ and H₂O into CO and H₂ by means of a gaseous hydrocarbon such as coke oven gas or natural gas by using the heat generated by the partial oxidation. Furnace top gas exhausted from a reducing furnace may be added to the partially oxidizing zone.

METHOD OF PREPARING REDUCING GAS

BACKGROUND OF THE INVENTION

This invention relates to a method of preparing reducing gas and more particularly to a method of preparing at high efficiencies reducing gas containing at least less than 7 % of CO_2 and H_2O and only a little quantity of free carbon by partially oxidizing a hydrocarbon while incorporating thereto oxygen or oxygen rich air. The invention also relates to a method for preparing at an extremely low cost reducing gas of the character described above by utilizing as the main raw material furnace top gas exhausted from the top of a reducing furnace, for example a blast furnace and containing CO_2 and H_2O .

By blasting reducing gas into a blast furnace or a shaft furnace it is possible to reduce the amount of coke which is required to be charged into the furnace to act as a reducing agent and hence to increase the amount of the iron ore charged in the furnace thereby improving the O/C ratio as well as the production of the cast iron. Regarding the preparation of reducing gas utilized for this propose, a member of methods have been proposed and practically used. Among these prior art methods may be mentioned a partial oxidation method wherein a hydrocarbon oil or hydrocarbon gas is caused to react with pure oxygen or oxygen rich air (containing more O_2 than 75 %), and a method wherein the gas exhausted from the top of a reducing furnace is modified by natural gas this preparing reducing gas by heat decomposition. However, these prior art methods have the following disadvantages. More particularly, in the partial oxidation method, in order to obtain reducing gas containing small quantities of CO_2 and H_2O by the partial oxidation reaction it is necessary that the percentage of pure oxygen to be incorporated into the hydrocarbon oil or hydrocarbon gas to a value be remarkably smaller than that required for an ordinary oxidation process. For example, when heavy oil is used as the raw material, unless the quantity of pure oxygen per one kilogram of the carbon contained in the heavy oil is decreased to about from 0.95 to 0.97 Nm^3 , it is impossible to effect the desired partial oxidation reaction. With such low percentage of oxygen it is inevitable to form a large quantity of free carbon or soot. For this reason, it is necessary to add a quantity of steam or the like to act as a moderator (soot preventing agent or a buffer). Addition of steam increases the quantity of H_2O in the resulting reducing gas and where reducing gas is blown into a blast furnace or a shaft furnace it consumes a large quantity of the reducing agent or coke charged in the furnace. Although it is possible to alleviate this difficulty by increasing the percentage of the pure oxygen, increase in the percentage of the pure oxygen increases the contents of CO_2 and H_2O in the resulting reducing gas thereby impairing the reducing capability thereof. The partial oxidation process is so carried out with appropriate compromise between soot content and character of the reducing gas. Although a suitable compromise can be attained by a suitable selection of the quantity of oxygen used, a substantial quantity of soot is inevitable as has been pointed out hereinabove. (at least more than 10g/ Nm^3 and in an extreme case more than 20g/ Nm^3).

According to the heat decompositon process, a hydrocarbon oil or a hydrocarbon gas is merely heat decomposed by the heat accumulated in a heat exchanger

so that it is necessary to accumulate heat in the heat exchanger by suitable means. The composition of the resulting reducing gas and the content of soot contained therein are determined solely depending upon the quantity of heat accumulated. Moreover, the operation is troublesome, and the composition and the temperature of the reducing gas are not always constant at the start and the end in the making of the gas. It is difficult to adjust the composition.

SUMMARY OF THE INVENTION

Accordingly, it is an object of this invention to improve the method of preparing reducing gas by the partial oxidation process so as to produce high quality reducing gas containing a small quantity of soot regardless of the ratio of oxygen to the raw material hydrocarbon oil or the hydrocarbon gas. Contrary to the prior art method of preparing reducing gas wherein the reducing gas is prepared by a single process step, it is a feature of this invention to use a combination of two process steps. In the first step the hydrocarbon is oxidized by incorporating therewith oxygen or oxygen rich air, whereas in a second step a gaseous hydrocarbon is incorporated into the intermediate gas produced by the first step so as to pyrolyze and improve the quality of the intermediate gas. This invention is suitable to reform a hydrocarbon by using CO_2 and H_2O in a furnace top gas with partial oxidation of the oil, as the above-mentioned two steps. According to the novel method of this invention it is not necessary to maintain a paricular ratio of oxygen to the raw material hydrocarbon as in the prior art partial oxidation process thereby enabling a desired partial oxidation reaction with a higher oxygen ratio in a wide range, with the result that the operation is greatly simplified and the formation of soot is greatly decreased. With this first step, the quantities of CO_2 and H_2O generated increase proportionally with the oxygen and the quantity of heat generated by the partial oxidation reaction also increases. However, the quality of the intermediate gas can be improved by the second step in which a gaseous hydrocarbon is incorporated and the resulting mixture is pyrolyzed. More particularly, in the second step, CO_2 and H_2O produced in the first step are converted into CO and H_2 which are advantageous for the reducing gas. Moreover, the heat generated in the first step is advantageously and reversibly used for the heat of pyrolysis. With these two steps, even if the composition of the intermediate gas resulting from the first step is not constant it is possible to adjust or improve the composition by the second step thereby making it possible to produce reducing gases of any desired composition or characteristic. Thus it is always possible to assure stable operation and to reduce the quantity of soot. Moreover, it is not necessary to prepare any source of heat necessary for the pyrolysis and improvement of the quality of the reducing gas.

Another object of this invention is to obtain reducing gas at a low cost. As has been pointed out hereinabove, since the method of this invention is easy to carry out and since it is not necessary to install any independent source of heat for the pyrolysis it is possible to greatly reduce the cost of manufacturing the reducing gas. Moreover, in accordance with the method of this invention exhaust gas exhausted from a reducing furnace such as a blast furnace and containing appropriate quantities of CO_2 and H_2O is used as the principal raw

material. It is possible to reduce the cost of manufacturing reducing gas by at least more than 30 % than the prior art methods described above. Usually, it is possible to reduce the cost by even more.

BRIEF DESCRIPTION OF THE DRAWING

Further objects and advantages of the invention will be more fully understood from the following detailed description taken in conjunction with the accompanying drawing in which a single FIGURE is a diagrammatic representation for explaining the process steps of the method of this invention.

DESCRIPTION OF THE PREFERRED EMBODIMENT

As shown in the accompanying drawing furnace top gas 2 exhausted from the top of a reducing furnace 1 such as a blast furnace and containing CO_2 and H_2O , is admitted into the heating section 4 of a gas manufacturing furnace 10 via dehydrating and dust removing device 3. In the furnace 10 are installed oxy-fuel burners 5 and 6 to atomize a hydrocarbon oil. Oxygen or oxygen rich air is admixed with the atomized hydrocarbon oil at a ratio in a range described above to effect a partial oxidation (combustion) or the first process step to form hydrocarbon gas which is mixed with the furnace top gas to act as the modifying gas. Furthermore, hydrocarbon gas such as coke oven gas 11 (H_2 : 45 ~ 55 %, CH_4 : 35 ~ 45 %, CO : 3 ~ 6 %, CmHn : 2 ~ 4 %) is admixed with said gas mixture in a reformer thereby effecting the pyrolysis of the second process step. More particularly, reducing gas of the desired quality is produced from a hydrocarbon oil without forming soot by supplementing by itself the heat required for the pyrolysis and by adjusting the atmosphere at the time of switching. The resulting reducing gas is admitted into the blast furnace 1 via a conduit 12. The gas is blown into the furnace through an inlet part 13 provided above the tuyers not shown. Thus, the reducing gas manufacturing furnace 10 of this invention is combined with the blast furnace 1 to effect partial oxidation of the top gas exhausted from the blast furnace and the resulting reducing gas is blown into and circulated through the blast furnace. This arrangement reduces not only the quantity of the discarded gas but also the heat loss, thereby assuring efficient operations both in the blast furnace 1 and the reducing gas manufacturing furnace 10.

The principle of operation of the method of this invention capable of being carried out by the arrangement described above is as follows :

The partial oxidation of a hydrocarbon of a hydrocarbon oil can be expressed by the following equation (I).

in which CmHn represents heavy oil, for example, and corresponds to a value of about 0.95 to 0.97 $\text{Nm}^3/\text{Kg}(\text{C})$ as in the prior art method. The value a amounts to from 2 to 6 % by volume based on the total quantity of the gas produced, b equals to 30 ~ 45 %, d equals to 18 ~ 60 %, and e equals to from 4 to 18 %. The value q represents the quantity of heat generated and in the partial oxidation process q_1 is used to increase the temperature of the resulting reducing gas. Of course this heat quantity is equal to the difference between the sum of the heat quantities generated by the

formation of CO_2 , CO and H_2O , and the heat of pyrolysis of CmHn , and these heat quantities per mole have the values as shown by the following equations (II) to (IV).

As can be noted from these equations, the heats of forming CO_2 and H_2O are much larger than that of CO expressed by equation (III). This means that increase in the value of α in equation (I) causes a large quantity of O_2 to react thus increasing the quantities of CO_2 and H_2O . This also increases the quantity of heat q_1 generated as can be clearly understood from equations (II) and (IV).

It is also possible to decrease the quantity of soot shown by f and c in equation (I) by increasing α . If α is increased to a value corresponding to about 2.6 to 3.0 $\text{Nm}^3/\text{Kg}(\text{C})$, f and c become substantially zero. Considering the characteristic of the reducing gas, although it is possible to reduce the quantity of soot ($f.c$) by increasing the value of α , the quantities of CO_2 and H_2O are also increased which is of course undesirable. For this reason, it is advantageous to limit the sum of CO_2 and H_2O in the resulting reducing gas not to exceed 10 % even though a small quantity of soot may be formed. To this end, the value of α should correspond to about 0.95 to 0.97 $\text{Nm}^3/\text{Kg}(\text{C})$. According to this invention, however, the CO_2 and H_2O components formed in a reducing furnace are decomposed by the hydrocarbon gas $\text{Cm}'\text{Hn}'$ as shown by the following equation (V).

Thus, the reaction process according to equation (V) to form reducing gas consisting essentially of $\text{CO} + \text{H}_2$, is endothermic so that it is necessary to supplement a heat quantity q' .

From the foregoing description it can be noted that the invention is characterized in that a hydrocarbon oil is partially burnt according to equation (I) with a value of α selected in a range not to form as far as possible soot and to form gas containing excess α quantities of CO_2 and H_2O . Thereafter an excess quantity of a gaseous hydrocarbon $\text{Cm}'\text{Hn}'$ is added to the gas for converting the CO_2 and H_2O into CO and H_2 , and a portion of the heat q_1 generated by the reaction of equation (I) is used reversibly as the heat for converting CO_2 and H_2O into CO and H_2 . In other words, chemical reactions expressed by the following equation (I') and (VI) proceed in parallel.

when $q.c$ represents the heat of forming $a\text{CO}_2$ and $e\text{H}_2\text{O}$

As can be noted from an equation of equilibrium of water gas reaction, although all of the CO_2 and H_2O are not always converted into CO and H_2 , according to this invention it is possible to select the value of α to have a value of 1.30 or more which is extremely larger than that utilized in the conventional partial oxidation process. Consequently the value of a amounts to from 7 to 10 % by volume based on the total volume of the gas

produced by the partial oxidation and the value of e amounts to form 20 to 30 % by volume. On the contrary, the value of $f.c$ is decreased thereby restricting the convention of the Conradson-carbon such as heavy oil into soot. By the incorporation of the gaseous hydrocarbon excess quantities of CO_2 and H_2O formed in accordance with the reaction expressed by equation (VI) are pyrolyzed and converted into CO and H_2 and the heats of reaction are expressed by the following equations.

Adding equations (VII) and (VIII),
 $\text{C oil} + \text{O}_2 + \text{CH}_4 \rightarrow 2\text{CO} + 2\text{H}_2 + 38.1 \text{ Kcal/mol} \quad (\text{IX})$

As can be noted from these equations, since the heat of reaction is used reversibly it is not necessary to supplement heat from outside. Even when the percentage of the reducing gas formed by the partial oxidation of the hydrocarbon expressed by equations (I') and (IX) is small with respect to the total volume of the gas there is no problem.

Referring again to the accompanying drawing, after 25 dehydration and dust removal, the furnace top gas 2 exhausted from reducing furnace 1 or blast furnace has a composition of 18~22 % of CO_2 , 2~50 % of H_2 and 8~57 % of N_2 , for example. After heating in the heating section 4, the gas is admitted into the reducing gas 30 manufacturing furnace 10 equipped with oxyfuel burners 5 and 6. The gas is then partially burnt by selecting a ratio O_2/oil of 1.30 $\text{Nm}^3/\text{Kg}(\text{C})$, for example, to produce intermediate containing higher contents of CO_2 and H_2O than the conventional method. The intermediate gas thus produced is then caused to react in the re-

5 → CO and $\text{H}_2\text{O} \rightarrow \text{H}_2$. The resulting reducing gas generally has a composition of 2~4 % of CO_2 , 30~40 % of CO , 18~60 % of H_2 and 4~36 % of N_2 , all in volume percent, and can be directly blown into the reducing furnace 1.

The same can also be obtained by incorporating a gaseous hydrocarbon into a partially oxidized hydrocarbon oil and then converting the mixture in the manner described above. In this case, since the gas ex-

10 hausted from the top of a reducing furnace is not used, the hydrocarbon oil is partially oxidized by the oxy-fuel burners 5 and 6 in the furnace 10 and the CO_2 and H_2O components contained in the resulting intermediate gas are pyrolyzed and converted into CO and H_2 in the reformer 8 by a gaseous hydrocarbon such as coke oven gas or natural gas.

15 In each case, the value of O_2 contained in the oxy-fuel used to partially oxidize the hydrocarbon oil should be in a range of from 1.00 to 3.00 $\text{Nm}^3/\text{Kg}(\text{C})$. 20 If this value decreases below 1.00 the quantity of soot formed increases thereby impairing the quality of the resulting reducing gas. On the contrary, when the value of oxygen exceeds 3.00, although the quantity of soot can be reduced to an extremely small value the result would be the same as if the hydrocarbon oil were burnt completely, thus increasing the quantity of CO_2 so that by converting this CO_2 by gaseous hydrocarbon it is impossible to produce valuable reducing gas.

25 Seven examples of this invention are shown in the following table together with two control example. The composition of the blast furnace gas utilized in these examples was : CO_2 , 18 %; CO , 23 %; H_2 , 2 %; and N_2 , 57 %; and the composition of the heavy oil was : C, 90.5%; Specific Gravity 20(A.P.I.), Pour Point 6 C. 30 The coke oven gas had a composition of CH_4 , 30 %; CmHn , 3 %; CO , 6 %; and H_2 , 55 %.

former 8 with the CH_4 and CmHn components of coke oven gas having a composition as shown in the drawing and preheated to a suitable temperature by heating furnace 7 thereby converting CO_2 and H_2O in the intermediate gas into reducing gases CO and H_2 . The heat quantities formed by the reactions $\text{C} \rightarrow \text{CO}_2$ and $\text{H}_2 \rightarrow \text{H}_2\text{O}$ are used for the endothermic reactions CO_2

65 As can be noted from this table the quantity of the soot formed differs greatly between the control examples wherein the quantities of O_2 in O_2/C in oil) are 0.95 and 0.92 Nm^3/kg and the examples of this invention wherein the quantities of O_2 exceed 1.0 Nm^3/kg . Especially in examples 4 to 7 the quantity of soot formed is below 2.0 g/Nm^3 . Test was also made wherein

the value of O_2 in $O_2/(C \text{ in oil})$ was selected to be higher than 3.00. In this case, the quantity of CO_2 generated in the first step was from 8 to 20% and that of H_2O was from 16 to 40 %. In order to pyrolyze the intermediate gas containing such amounts of CO_2 and H_2O it was necessary to use a greater quantity of coke oven gas of the order of 300 Nm^3/hr than the case shown in example 7.

From the forgoing description it can be noted that the invention provides a novel method of preparing reducing gas without regard to the ratio of oxygen to fuel which is the most important factor in the method of manufacturing reducing gas by partial oxidation process, thus making it possible to produce valuable reducing gas by selecting the ratio of higher than unity and to greatly decrease the quantity of soot formed. Moreover, according to this invention, the intermediate gas is converted by a gaseous hydrocarbon to obtain reducing gas having excellent composition and characteristic and can be advantageously used in such reducing furnaces as a blast furnace. Furthermore, the partial oxidation reaction which is inherently an endothermic reaction is caused to proceed in parallel with the conversion of the furnace top gas by hydrocarbon gas thus making it possible to use furnace top gas as the main raw material. Thus, the heat of reaction is efficiently utilized to control the composition and temperature of the reducing gas formed so that it is possible to prepare valuable reducing gas at an extremely low cost.

Although the invention has been described in terms of particular examples thereof it should be understood that many changes and modifications will be obvious to one skilled in the art without departing from the true spirit and scope of the invention as defined in the appended claims. What is claimed is:

1. A method of preparing reducing gas comprising the steps of

partially oxidizing a hydrocarbon with oxygen or oxygen-rich air to form an intermediate gaseous product containing CO_2 and H_2O , wherein heat is generated, the quantity of oxygen being from 1 to 3 Nm^3/Kg of carbon contained in said hydrocarbon, and

pyrolyzing said intermediate gaseous product and a gaseous hydrocarbon with said heat whereby said CO_2 and H_2O are converted into a reducing gas containing CO and H_2 .

2. The method according to claim 1 wherein said hydrocarbon is a hydrocarbon oil and said gaseous hydrocarbon is coke oven gas or natural gas.

3. A method of preparing reducing gas comprising the steps of

atomizing and partially oxidizing a hydrocarbon oil with oxygen or oxygen-rich air, wherein heat is generated, the quantity of oxygen being from 1 to 3 Nm^3/Kg of carbon contained in said hydrocarbon oil,

admixing the resulting gas with a furnace top gas exhausted from a reducing furnace to form an intermediate gas containing CO_2 and H_2O , and

incorporating a coke oven gas or a natural gas with said intermediate gas and pyrolyzing the resulting mixture with said heat, whereby said CO_2 and H_2O are converted into a reducing gas containing CO and H_2 .

4. The method according to claim 3 wherein said reducing gas is blown into said reducing furnace.

5. The method according to claim 4 wherein said reducing furnace is a blast furnace.
